Leonard E. Finch, West Bend, Wis., assignor to
West Bend Aluminum Co., West Bend, Wis., a
corporation of Wisconsin

Application October 7, 1949, Serial No. 5,346

Term of patent 14 years

(Cl. D44—29)

To all whom it may concern:

Be it known that I, Leonard E. Finch, a citizen of the United States, residing at West Bend, in the county of Washington and State of Wisconsin, have invented a new, original, and ornamental Design for an Egg Rack, of which the following is a specification, reference being had to the accompanying drawing forming a part thereof, and in which:

Fig. 1 is a perspective view of an egg rack showing my new design;

Fig. 2 is a top plan view; and

Fig. 3 is an elevational view thereof.

I claim:

The ornamental design for an egg rack, as shown.

LEONARD E. FINCH.
